Att'y.

UNITED STATES PATENT OFFICE.

GEORGE B. MALTBY, OF CLEVELAND, OHIO, ASSIGNOR TO CLEVELAND CAR SPECIALTY COMPANY, OF CLEVELAND, OHIO, A CORPORATION OF WEST VIRGINIA.

ROOF-CARLINE.

No. 824,940.

Specification of Letters Patent.

Patented July 3, 1906.

Application filed August 2, 1905. Serial No. 272,827.

To all whom it may concern:

Be it known that I, GEORGE B. MALTBY, of Cleveland, in the county of Cuyahoga and State of Ohio, have invented a certain new and useful Improvement in Roof-Carlines, of which improvement the following is a specification.

My invention relates to sheet or plate metal roof carlines of the general type which is exemplified in Letters Patent of the United States No. 649,171, granted and issued to me and to Broderick Haskell (as assignee of two-thirds of the right) under date of May 8, 1900.

The object of my present invention is to provide a roof - carline embodying the advantageous features of that set forth in Letters Patent No. 649,171 aforesaid and which shall further afford improved facilities for being supported on the car side plates and for acting as a tie between the opposite sides of the car.

The improvement claimed is hereinafter fully set forth.

In the accompanying drawings, Figure 1 is a side view, in elevation showing slightly more than one-half in length of a roof-carline embodying my invention; Fig. 2, a plan or top view; Fig. 3, an end view; Fig. 4, a transverse section on the line *a a* of Fig. 1; and Fig. 5, a similar section indicating the lateral flanges as extending throughout the length of the carline.

In the practice of my invention I provide a roof-carline which is formed of sheet or plate metal, preferably by being pressed or shaped in a die or mold. The body of the carline is integral and comprises a web 1 of inverted U or channel transverse section and lateral flanges 1^a, projecting from the bottoms of the opposite side members of the web. As shown in Figs. 1, 2, and 4, the flanges 1^a extend from each end of the body for a portion only of its length— as, say, about one-sixth thereof—and are tapered inwardly or toward the middle of the carline; but, as indicated in Fig. 5, said flanges may, if desired, extend throughout its entire length. The web 1 is downwardly inclined from its middle to each of its ends at such an angle as may be adapted to impart the desired pitch to the roof. It is also

preferably, as shown, diminished in depth from its middle portion toward each of its ends for a comparatively short distance—as, say, about one-sixth of its length from each end; but it may, if desired, be made of uniform depth throughout.

The ends of the carline extend completely over and are supported on the side plates of the car-frame, (indicated in dotted lines at the left of Fig. 1,) and in order to provide for the secure attachment of the carline to the side plates and the connection of the opposite sides of the car, so as to dispense with the usual tie-rods, downwardly-turned flanges 1^d are formed on the ends of the body 1, said flanges abutting against the outer faces of the side plates and being secured thereto by horizontal bolts passing through holes 8^b in the flanges. Holes 8^a are also formed in the lateral flanges 1^a of the body for the reception of vertical bolts by which said flange are connected to the side plates.

To provide suitable bearings for the ridge-pole and purlins of the roof, the metal of the web 1 is turned downwardly at the middle of the carline and at proper distances between the middle and the ends, so as to form seats 6 of channel-section in which the ridge-pole and purlins are fitted and to which they are secured by bolts passing through holes 8 in the seats.

The practical advantages of strength, lightness, and facility of application in ordinary car - framing which are presented by my improvement will be obvious to those familiar with railroad-car construction, and it will also be apparent that it may be employed in connection with a car-roof of any desired type.

I claim as my invention and desire to secure by Letters Patent—

1. A sheet or plate metal roof-carline having an integral body comprising a web of inverted U or channel section, lateral flanges projecting from the side members thereof, and downwardly-turned flanges at the ends of the web and lateral flanges, forming uninterrupted flat end walls to the channel or U.

2. A sheet or plate metal roof-carline having an integral body comprising a web of in-

verted U or channel section, the side members of which are of uniform depth for some distance on each side of its center, and thereafter diminish in depth toward its ends, lateral flanges projecting from the side members of the web, and downwardly-turned flanges at the ends of the web and lateral flanges, form-

ing uninterrupted flat end walls to the channel or U.

GEORGE B. MALTBY.
